ALBERT LEFEBVRE, OF PRE-ST.-GERVAIS, FRANCE.

LUBRICATING APPARATUS WITH MULTIPLE PUMPS.

Application filed March 30, 1928, Serial No. 266,015, and in France February 7, 1928.

In lubricating apparatus adapted to deliver consistent grease under pressure, by the use of a certain number of individual pumps under the proper control of the machine, great difficulties are always found, due to the nature of the said grease, in the supply of each of the pumps. The grease settles in a defective manner, leaving air pockets, and all means for obviating this difficulty have been found too complex and therefore expensive, or their operation is defective.

All such defects are obviated by the present invention.

Upon a cylindrical pump barrel or main body are mounted various individual pumps, actuated by suitable means, and the said body contains a plurality of scrapers whereof a certain number are fixed and the rest movable, the latter being driven for instance by a central shaft actuating the pumps.

The movable scrapers drive forward the consistent grease; they are inclined in such manner that the grease will tend to pass below the scrapers, being thus brought to the end of the apparatus, but when used alone they would not produce the necessary pressure to force the said grease into the pumps, for at a certain time the grease forms a single body with the scrapers and is thus drawn in the circular direction, so that the scrapers will not drive it towards the pumps. It is therefore advantageous to use stationary obstacles or scrapers between the said movable scrapers. At each revolution, since the fixed scrapers are preferably inclined contrary to the movable scrapers, the grease will accumulate thereon until the rotation brings the movable scrapers to this point so that they will take up the grease and will again drive it towards the pumps.

By this arrangement of fixed and movable scrapers the pressure is increased in such manner that the grease accumulates at the end of the recipient and no air pockets will be formed.

In certain cases, the arrangement may be still insufficient to cause the grease to flow regularly through the orifices corresponding to the pumps, these latter having necessarily a reduced size to allow the proper adjustment and to obtain a delivery of grease according to needle.

To oblige the grease to pass through the said orifices and to entirely fill the pumps, I may provide in the end of the main body or grease recipient suitable chambers corre-

sponding to the respective pumps, each chamber being open at the top and closed below the pump. The lower scraper is preferably adapted to oscillate through a certain angle upon its axis, and it is downwardly urged by a spring. When proceeding upon each chamber, the spring forces the scraper into the recess of this chamber; the partition between this chamber and the next will then raise the said scraper, and due to this motion the grease will be assembled between the scraper plate and the partition of the chamber, thus producing an additional pressure in the said chamber and assuring an approved circulation of the grease into the respective pump.

If the pumps employed are not adapted for the use of chambers, the end of the main body may be properly shaped by means of saw cuts, and the end of each saw cut will correspond to the feeding orifice for the respective pump. The oscillating scraper operates in the same conditions as above mentioned; it offers like results as to additional compression of the grease and assures the proper supply in an efficient manner.

The appended drawings show by way of example an embodiment of the invention.

Fig. 1 is one-half of a vertical section of the apparatus on the axis of the driving shaft, and,

Fig. 2 is the corresponding plan view.

Fig. 3 is a section on the lines III—III of Fig. 2.

Fig. 4 is a section on the line IV—IV of Fig. 3.

Fig. 5 is a view analogous to Fig. 3 relative to a modified construction.

The apparatus comprises a main body 1 upon which are mounted the pumps 6 under the control of a cam 7 disposed on the central shaft 2. The said pumps are preferably of the type represented, thus comprising a pump barrel 8, a stationary piston 9, and a movable piston 10 for the delivery; 25 represent the inlet orifices, 26 is the slack valve under the control of a spring 27 and 28 is the delivery conduit. A knob 11 serves to adjust the position of the piston 9 with reference to the piston 10, in such manner as to increase or diminish the amount of lubricant supplied.

At the end of the barrel 1 are provided the chambers 12, in the same number as the pumps, said chambers being separated from one another by the vertical partitions 13.

- Above the said chambers are mounted a certain number of scrapers, three for instance, 15—16—17; the scrapers 15 and 17 are secured to the shaft 2 and turn with it; 5 the scraper 16 is loose on the shaft and is held by a stop 18 mounted on the barrel 1. The first scraper 15 makes friction contact with the said chambers, as above mentioned; for this purpose it is pivotally 10 mounted on an axle 19 secured to a hub 19^a which rotates with the shaft 2, and it is thus enabled to enter the chambers 12 under the action of a spring 21.
- The pivoting plate 15 may be dispensed 15 with and a plate such as 17 substituted. The number of the scrapers may vary according to the number of the chambers; starting from the end, the first scraper is always movable and the second stationary.
- 20 The shaft extends above the last scraper for a distance sufficient to dispose the spring 22 and the nut 23, so that the lubricant will not lift the scrapers, while at the same time the set of scrapers will have the elasticity required for the proper functioning.
- In the modification shown in Fig. 5, the chambers provided on the end of the barrel 1 are formed by means of saw cuts 29 formed in the metal of this end part. 30 is the admission orifice in the pump body 31.
- Having thus described my apparatus, what I claim as new therein, and my own invention, is:—
1. A lubricating apparatus, comprising a grease recipient, a plurality of pumps disposed at the lower part of said recipient, means for driving the said pumps, at least one scraper rotatable in said recipient, said scraper being inclined in such manner as 35 to force the grease to the lower part by its rotation, and an obstacle disposed above the said scraper and adapted to prevent the grease from being drawn forward in a single mass by the said rotating scraper.
  - 40 2. A lubricating apparatus provided with a plurality of individual pumps, comprising a grease recipient, a plurality of pumps disposed at the lower part of said recipient, a driving shaft mounted at the centre of said recipient, a cam disposed on said shaft for actuating the pumps, at least one inclined scraper secured to the said recipient, and at least one rotatable scraper mounted on the said shaft, it being inversely inclined with reference to the fixed scraper 45 and placed below the latter.
3. A mechanically operated lubricating apparatus containing individual pumps, which comprises a grease recipient, a plurality of pumps in radial disposition at the lower part of the said recipient, a driving shaft mounted at the centre of the said recipient, a cam disposed on said shaft for actuating the pumps, a rotatable scraper mounted on said shaft above the said pumps, or said scraper comprising a plate whose rear part is downwardly pressed by elastic means, and a stationary scraper disposed in the contrary direction to the preceding and placed above the same. 170
4. A mechanically operated lubricating apparatus containing individual pumps, which comprises a grease recipient, a plurality of pumps in radial disposition at the lower part of said recipient, radial partitions provided upon the bottom of said recipient and forming as many chambers as there are pumps, the suction orifice of each pump opening into one of the respective chambers, a driving shaft mounted at the 75 centre of said recipient, a cam disposed on said shaft for actuating the pumps, a rotatable scraper mounted on said shaft above the said pumps, said scraper comprising a plate whose rear part is downwardly pressed by elastic means in such manner as to operate by friction upon the upper part of said radial partitions and to enter the said chambers, and a stationary scraper disposed in the contrary direction to the preceding and placed above the same. 80
- In testimony whereof I have hereunto affixed my signature.
- ALBERT LEFEBVRE.
